CLAIM

The ornamental design for a mounting bracket for roof mounted photovoltaic modules, as shown and described.

DESCRIPTION

FIG. 1 is a perspective view of a mounting bracket for roof mounted photovoltaic modules according to the design; FIG. 2 is a front devotional view thereof, the rear elevational view being a mirror image;

FIG. 3 is a side elevational view thereof, the opposite side elevational view being identical;

FIG. 4 is a top plan view thereof; and,

FIG. 5 is a bottom plan view thereof.

1 Claim, 5 Drawing Sheets
